STORE FRONT CONSTRUCTION

William Owen, Pittsburgh, Pa., assignor to Pittsburgh Plate Glass Company, Allegheny County, Pa., a corporation of Pennsylvania

Application November 18, 1937, Serial No. 175,205

6 Claims. (Cl. 20—56.4)

The present invention relates to store front constructions and it has particular relation to the sash construction by means of which large plates of glass are secured in position.

One object of this invention is the provision of a simple store front construction, which can be assembled with minimum labor. The invention further contemplates a construction in which the component elements are positively locked together and are releasable only from the rear thereof.

Other objects and advantages of my invention will become more apparent from the following detailed description.

Certain embodiments of the invention are shown in the accompanying drawings, wherein: Figure 1 is a vertical sectional view of a store front construction as contemplated by my invention. Figure 2 is a vertical sectional view along a different plane through the construction shown in Figure 1. Figures 3 and 4 are, respectively, isometric views of a sash bar and a cover plate, constituting parts of the construction. Figures 5, 6 and 7 are isometric views of various styles of supporting blocks for the glass plate. Figure 8 is an isometric view of a spring clip especially adapted for positioning the block shown in Figure 7. Figures 9, 10 and 11 are vertical sectional views of additional embodiments of the invention.

Referring to the drawings, a sash frame or casement 1 of the usual wood construction is rabbeted along its outer edge to provide a groove 2 and is covered with a metal plate or sheathing 3 attached thereto by means of countersunk screws 4 spaced at suitable intervals. The casement 1 serves as a seat for the sash construction 5, which is secured therein.

The construction 5 comprises a sash bar 6, preferably of extruded aluminum or other suitable metal, which includes a vertical back strip 7 and a horizontal base strip 8, the two strips being joined by an obliquely disposed web 9. A forwardly projecting flange 10 is formed along the upper edge of the back strip 7 and is provided along its forward edge with a downwardly extending locking lip 11 comprising an upper portion 12 and a lower portion 13 rearwardly offset therefrom and connected thereto by an obliquely extending web 14. The lip 11 extends almost to the base strip 8 and the portion 13 is provided with spaced notches 15, the function of which will be described later. The sash bar 6 is secured to the casement 1 by any suitable means, as for

example by screws 16 passing through openings 17 provided therein.

Blocks 19 for supporting a plate 20 of glass are positioned along the base strip 8 within the notches 15 provided in the portion 13 of the lip 11, as shown in Figure 5. The blocks 19 may be entirely of leather or other resilient and pliable material or, as shown in Figure 6, they may have a base 21 of metal to which is attached by means of countersunk rivets 22 a layer 23 of resilient material which projects beyond the ends of the base 21. Slots 24 are provided in the block 19 or resilient layer 23 to receive the section 13 of the lip 11, the inherent pliability of the material in which the slots 24 are formed permitting the lips 15 of the slots to be sprung when the blocks are inserted in the openings 15.

In the construction, as illustrated in Figures 7 and 8, the supporting block comprises a metal base 25, the upper surface of which is grooved to receive a strip 26 of resilient material, such as leather. The supporting blocks are secured in the notches 15 formed in the section 13 of the lip 11 by means of spring clips 27. The clips 27 comprise an intermediate portion 28 reflexly bent at the ends to provide lugs 29 which engage the rear face of the section 13. The clip is bent forwardly from the lugs 29 to provide shoulders 30 that engage the ends of the base 25, and again reflexly bent inwardly to provide a second set of lugs 31 that engage the forward face of the block. From the lugs 31, the clip is bent obliquely and rearwardly to engage the forward face of the lip section 13, thus locking the clip and block in position into the notch 15. The resiliency of the clip 27 is sufficient to permit it to be bent slightly as it is being inserted or removed from the notch 15 without entailing permanent distortion.

The glass plate 20, the inner surface of which rests against the upper portion 12 of the lip 11 carried by the flange 10 of the sash bar 6, is held in position by means of a cover plate 32, shown in Figure 4. The cover plate 32, preferably formed of extruded aluminum in any desirable cross-sectional outline, is provided with a downwardly extending rib 33, which engages the outer surface of the glass plate 20, and an inwardly projecting flange 34 having spaced notches 35 positioned therein to receive the supporting blocks 19. The flange 34 slidably engages the base strip 8 of the sash bar 6 and the upper surface of the flange has serrulations 36 engaging the lower edge of the locking lip 11. Screws 37 passing through openings 38 project through the flange 10 and the base strip 8 of the sash bar 6.

into the casement 1 and permit regulation of the pressure exerted by the locking lip 11 upon the flange 34 and insure a positive locking of the cover plate 32 in the construction. The screws 5 37 may be loosened to permit the construction to be dismantled, when such action becomes necessary.

In the modification, illustrated in Figure 9, the base strip 40 of the sash bar 41, corresponding to the sash bar 6, is provided with a plurality of pockets 42 which receive heads 43 of bolts 44 extending upwardly therefrom through the flange 10. The tension exerted by the locking lip 11 is obtained by nuts 45 secured to the bolts 44. The nuts 45 may be loosened to permit the construction to be dismantled.

The modification of my invention as illustrated in Figure 10 is substantially the same as that illustrated in Figures 1 and 2, with the exception that the locking means are not integral with the flange of the sash bar. The sash bar 6 is provided with a flange 43, corresponding to the flange 19 in Figure 1, which carries along its edge a reflexly bent lip 49, forming a downwardly opening channel 50. The forward face of the lip 49 engages the inner surface of the glass plate 20 and the channel 50 provides a bearing for the upper edge of a locking plate 51. The plate 51 is provided with openings 52 having tubular flanges 53 disposed thereabout. The enlarged cylindrical heads 54 of screws 55 extend within the flanges 53 and helical springs 56 disposed about the flanges 53 and the screw heads 54 maintain a positive outward pressure upon the plate 51. In this way the plate 51 is brought into engagement with the flange 34 of the cover plate 32. When it becomes desirable or necessary to remove the cover plate 32, the flange 48 may be lifted by means of any convenient instrumentality inserted through openings (not shown) in the flange to relieve the pressure exerted by the locking plate 51 against the flange 34, thus permitting the cover plate 32 to be moved away from the glass plate 20.

45 A further modified construction is illustrated in Figure 11, wherein a flange 60, corresponding to the flange 48, is provided at its forward edge with a downwardly extending lip 61 which engages the rear face of the glass plate 20. The flange 34 of the cover plate 32 is locked in position by means of springs 62 substantially of inverted V-shape. One branch 63 of the spring is secured against the vertical back strip 7 of the sash bar 6 by means of a screw 64. The apex 55 of the spring 62 rests in the angle between the flange 60 and the lip 61 and the second branch 65 of the spring extends downwardly into engagement with the flange 34.

The mode of operation and the advantages of 60 these constructions will be readily apparent to those skilled in the art. In the embodiment shown in Figures 1 and 2, the sash bar 6 is placed around the casement 1, the supporting blocks 19 are mounted in the sash bar and the glass plate 20 is positioned thereon. The assembly is completed by sliding the cover plate 32 into position. The locking lip 11 is so constructed that it will allow the flange 34 of the cover plate 32 to be advanced inwardly, but at the same time it resists any outward movement. After the cover plate 32 has been installed, the screws 37 are tightened to exert additional force upon the locking lip 11, which in turn is communicated to the flange 34 to clamp the latter against the base strip 8 of the sash bar. The modified construc-

tion shown in Figure 9 is assembled in the same manner, the component elements being locked together by the bolts 44 and the nuts 45 increasing the force exerted by the lip 11 on the flange 34.

5 Operation of the embodiments of the invention shown in Figures 10 and 11 is essentially the same as that shown in Figures 1, 2 and 9. The spring actuated plate 51 or the springs 62 simply replace the locking lip 11.

10 In the foregoing constructions the sash bars and cover plates act directly as gripping means for the plates of glass. The inherent resiliency of the various parts and notably the flanges 10, 15 48 and 60 is sufficient to permit adjustments to various strains which may arise. Accordingly, the component elements will not be permanently distorted nor will there be a loss of the gripping action upon the glass.

15 It is to be understood that various changes in the shape, size and arrangements of parts as set forth in the form of the invention herewith shown and described may be resorted to without departing from the spirit of the invention or the scope of the appended claims.

20 What I claim is:

1. In combination in a store front construction, a metal sash bar including a back strip, a base strip extending at right angles thereto, a flange also extending at right angles to the back strip in spaced relation to the base strip, and a locking plate extending downwardly from the flange in spaced parallel relation to the back strip, a glass plate supported in spaced relation from the sash bar and contacting the flange thereof and a metal cover plate provided with an inwardly projecting flange, contacting the outer surface of the glass plate and slidably engaging the base strip of the sash bar, the plate dependent upon and extending downwardly from the flange of the sash bar contacting the inwardly projecting flange of the cover plate to clamp it securely to the base strip.

2. In combination in a store front construction, a metal sash bar including a back strip, a base strip extending at right angles thereto, a resilient flange also extending at right angles to the back strip in spaced relation to the base strip, and a locking plate extending downwardly from the flange in spaced parallel relation to the back strip, supporting blocks positioned at intervals along the base strip, a glass plate seated upon the supporting blocks and contacting the resilient flange extending from the sash bar, a metal cover plate provided with an overhanging lip contacting the outer surface of the glass plate and an inwardly projecting flange slidably engaging the base strip of the sash bar, the locking plate dependent upon and extending downwardly from the resilient flange of the sash bar contacting the inwardly projecting flange of the cover plate to clamp it securely to the base strip, and means operable from the rear of the glass plate to control the pressure exerted by the locking plate upon the flange of the cover plate.

3. In combination in a store front construction, a metal sash bar including a back strip, a base strip extending at right angles thereto, a resilient flange also extending at right angles to the back strip in spaced relation to the base strip, and a locking plate extending downwardly from the flange offset therefrom in spaced parallel relation to the back strip, resilient supporting blocks positioned at intervals along the base strip in openings provided in the locking plate, a glass

plate seated upon the supporting blocks and contacting the resilient flange extending from the sash bar, a metal cover plate provided with an overhanging lip contacting the outer surface of the glass plate and an inwardly projecting flange notched to clear the supporting blocks and slidably engaging the base strip of the sash bar, the locking plate extending downwardly from the resilient flange of the sash bar and contacting the upper surface of the inwardly projecting flange of the cover plate to clamp it securely to the base strip, and adjustable tensioning means extending through the resilient flange and the base strip of the sash bar operable from the rear of the glass plate to control the pressure exerted by the locking plate upon the flange of the cover plate.

4. A construction as defined in claim 3, in which the adjustable tensioning means are screws.

5. In combination in a store front construction, a metal sash bar including a back strip, a base strip extending at right angles thereto and a resilient flange also extending at right angles to the back strip in spaced relation to the base strip, the resilient flange having a downwardly extending lip, a glass plate supported in the sash bar and contacting the lip of the resilient flange

thereof, a metal cover plate contacting the outer surface of the glass plate and provided with an inwardly projecting flange slidably engaging the base strip of the sash bar, and a locking plate supported from the back strip of the sash bar in spaced relation thereto engaging the flange of the cover plate and clamping it positively to the base strip. 5

6. A store front construction comprising a frame having a rabbet extending about the inner periphery thereof, a plate of glass having its edges disposed in the rabbet, a cover plate disposed in front of the plate of glass having a lip along the edge thereof engaging the front face of the glass and having a horizontal rearwardly-projecting flange along the lower edge thereof disposed in the rabbet in the frame and extending under the edges of the glass plate, an upwardly-extending clamping plate disposed in the rear of the glass plate and having the lower edge thereof 10 engaging the flange of the cover plate, said clamping plate being secured to the rear wall of the rabbet in the frame and means actuating the clamping plate downwardly against the flange to clamp the latter in position, the lower portion of 15 the clamping plate being rearwardly offset with respect to the upper portion. 20

WILLIAM OWEN.
